WALL SUPPORTED CONTAINER LID CLAMP

Frank J. Niblett, Tracy, Calif.

Application April 10, 1948, Serial No. 20,185

2 Claims. (CL. 81—3.3)

1

This invention relates to jar openers and more particularly to a device for holding screw lids to facilitate the opening or unscrewing of lids from the containers.

In attempting to remove a screw lid or cover from a container it is often impossible to remove the lid using only one's hands to grasp the container and lid because of the slipping between the hands and said container and lid.

There have been numerous devices in the past to hold the lid or cover of containers while being loosened but they have not fully solved the problem of effectively holding such lids, nor have they been easily adjustable to accommodate the various sizes of lids in which food or other products are packed.

The primary purpose of the present invention, therefore, is to provide a device for conveniently and easily holding the screw lid of any container, such as a bottle, can or jar, for loosening such lid from the container.

Another object of the invention is to provide means to effect quick and simple adjustment of the jaws of the device to accommodate different sizes of lids.

A still further object of the invention is to provide means for moving and holding the clamping jaw in its clamped position.

Another object is to provide for the proper angular location of one of the clamping jaws for its proper contact with the circular edge of the lids of various sizes.

A further object of the invention is to produce a practical device and one which will be exceedingly effective for the purpose for which it is designed.

These objects are accomplished by means of such structure and relative arrangement of parts as will fully appear by a perusal of the following specification and claims.

In the drawings:

Figure 1 is a perspective view of a screw lid holder or clamp made in accordance with the construction of my invention.

Figure 2 is a side elevational view of the screw lid holder with the supporting wall in vertical section; the device being adjusted to hold a relatively small lid.

Figure 3 is a view similar to Fig. 2 but with the holder adjusted to accommodate a larger screw lid.

Figure 4 is a plan view of the holder with the supporting wall in horizontal section.

Referring now more particularly to the characters of reference on the drawings, the lid

2

clamp is supported on a bracket 1 having screw openings 2 with screws 3 extending therethrough into a wall 4. The bracket 1 has a horizontal portion 5 having a pivot pin 6 secured thereto and extending vertically therefrom.

The lid clamp has a vertically positioned mounting plate 7 which is bent to the form of a vertical cylindrical eye 8 that, when in assembled position, is located around the pin 6, supporting the mounting plate outwardly horizontally therefrom. Means are provided for preventing rotation of the mounting plate 7 on the pivot pin 6, which includes a pin 9 attached to and extending radially outwardly from the pin 6 and the eye 8 is provided with a notch 10 extending upwardly from the lower end thereof. The mounting plate may be swung around the pin 6 by lifting the mounting plate vertically until the notch 10 is free from the pin 9 and thereafter rotating the plate.

Adjustably mounted on the mounting plate 7 is a relatively stationary jaw 11 having a concave serrated engaging surface 12 and a rearwardly extending ear 13 on which it is pivotally mounted at 14 to an arcuately shaped jaw mounting bar 15. This bar has an arcuate slot 16 and a pair of pins 17, secured to the mounting plate 7, extending therethrough for guided arcuate movement to the bar 15. Means are provided for adjustably holding the bar 15 in any desired position for adjusting the jaw 11 to accommodate the holding of various sizes of screw lids. This adjusting means includes serrations 18 formed along the rear edge of the bar 15 and a ratchet dog 19 pivotally mounted at 20 on the mounting plate 7 adjacent the serrations 18 on the bar 15. A pin 21 extends from the mounting plate and is engaged by the dog 19, limiting its inward pivotal movement. The dog 19 has an integral operating finger 22 whereby the dog may be released manually from engagement with the serrations 18 on the bar 15. A wire spring 23 is welded or otherwise secured to one side of the eye 8, the free sprung end thereof engaging the finger portion 22 of the ratchet dog 19 thereby yieldably holding the dog in engagement with the serrations 18. By releasing operation of the finger 22, the bar 15 and the stationary jaw 11 may be adjusted to accommodate the holding of various sizes of screw lids.

A movable clamping jaw 24, having a concave serrated lid engaging surface 25 is pivotally mounted at 26 on the mounting plate 7 and contacts with the adjustable stationary jaw 11 to hold

a screw lid to facilitate the tightening or the loosening thereof on a container. Means are provided for forcibly moving the movable jaw toward the stationary jaw and includes a roller 21, rotably mounted at 28, on the inner end of a manually operable clamping arm 29 pivotally mounted at 30 to the mounting plate. The pivot pin 28 is a short radial distance from the pivot pin 30 whereby the roller 21 has an eccentric movement around the pivot 30 and by pivotal movement of the arm 29 the roller 21 forcibly moves the movable jaw 25 toward the stationary jaw 11. A wire spring 31 is secured at 32 to the mounting plate 7 closely adjacent the movable jaw 25 with its free sprung end engaging the jaw thereby yieldably holding the jaw against the roller 21.

Operation

The lid clamp is attached to a wall 4, as shown, with the notch 10 engaging the pin 9 holding the opener in extended operative position on the bracket 1. By movement of the finger 22, the dog 19 is moved to released position from the ratchet teeth 18 on the bar 15. The adjustable stationary jaw 11 is moved to the proper adjusted position to hold the size of lid desired to be held for tightening or loosening on a container. The lid is located against the stationary jaw 11 and the movable jaw 24 is moved forcibly against the opposite side of the lid by manual pivotal movement of the operating arm 29, eccentrically moving the roller against the jaw 24. The lid is thus held so that the container desired to be screwed thereon or therefrom may be readily grasped as the lid is held from slipping while the container is rotated. The loosening of the lid on the container is thus facilitated or aided by the positive holding of the lid during the operation. By releasing the ratchet dog 19 from the ratchet teeth on the arcuate bar 15, the distance of the stationary jaw from the movable jaw may be regulated to receive and hold various sizes of lids.

From the foregoing description it will be readily seen that there has been produced such a device as substantially fulfills the objects of the invention as set forth herein.

While this specification sets forth in detail the present and preferred construction of the device, still in practice such deviations from such detail may be resorted to as do not form a departure

from the spirit of the invention, as defined by the appended claims.

Having thus described the invention, the following is claimed as new and useful and upon which Letters Patent is desired:

1. A container lid holding device comprising a mounting plate, a jaw supporting bar, means mounting the bar on the plate for arcuate sliding movement, ratchet teeth on one edge of the bar, a ratchet dog pivotally mounted on the plate, means yieldably holding the dog in engagement with the ratchet teeth, a concave jaw pivotally mounted on one end of the bar, a second jaw mounted on the plate for movement toward and away from the first jaw, and means mounted on the plate and operable to move the second jaw.

2. A container lid holding device comprising a mounting plate, a jaw supporting bar provided with an arcuate slot, spaced apart pins projecting through the slot and secured in the plate, the bar being slidable over the pins, means on the plate acting on the bar to yieldably hold the same against such sliding movement, a concave jaw pivotally mounted on one end of the bar, a second jaw mounted on the plate for movement toward or away from the first jaw, and means mounted on the plate and operable to move the second jaw.

FRANK J. NIBLETT.
